UNITED STATES PATENT OFFICE.

EDWARD J. READING, OF PATERSON, NEW JERSEY.

PACKET CONTAINER.

Application filed December 2, 1926. Serial No. 152,075.

Many women who smoke cigarettes have a hesitancy about displaying the ordinary cigarette package in certain public places, and most women would prefer to substitute 5 for the display of the trade mark and the like which the ordinary cigarette package carries a wrapping which in structure and general character would be more in keeping with feminine taste. With the object of 10 providing, therefore, a case into which a package of cigarettes may be slipped and thus concealed which will be attractive in respect both to its appearance and to the manner in which it is operated for access to the 15 cigarettes or for removal of the empty package and introduction of a fresh one I have devised the present invention.

In the drawings,

Figs. 1 and 2 are, respectively, perspective rear and front views of one form of the case and contained package, respectively showing the case open and closed;

Figs. 3 and 4 are sectional views on lines 3—3 and 4—4, respectively of Figs. 1 and 2, 25 the package being shown in side elevation, partly broken away, and a certain strap in broken lines, in Fig. 4;

Figs. 5 and 6 show the blank from which the case is made, Fig. 6 illustrating particularly how the flap thereof is folded;

Fig. 7 shows the blanks from which a modified form of the case is made;

Figs. 8 and 9, are, respectively, a front and side elevation, each partly broken away, 35 of this form of the case, with the package therein; and

Fig. 10 is a horizontal sectional view on line 10—10, of such form and contained package.

Wherever the cigarettes appear in the drawings they are designated 1 and the package or wrapper therefor 2.

Describing, first, the form of case shown in Figs. 1 to 6: 3 is a rectangular elongated blank of sheet material. It is to be folded to produce a hollow rectangular body open at one end and for this purpose its folds will be as follows: Two longitudinal folds 3^a parallel with and near its longitudinal edges; 50 two transverse folds 3^b spaced about the same as the cigarette package is thick and arranged somewhat nearer one end of the blank than the other; a transverse fold 3^c which is to intervene between the body of the case and its flap; end transverse folds 3^d, 3^e; and short oblique folds 3^f reaching

from its longitudinal edges to the juncture of folds 3^a, 3^b. The rectangle bounded by the two folds 3^a and the two 3^b will form the bottom I or closed end of the package 60 when the portions to right and left thereof in Fig. 5 are folded upward on lines 3^b to form the two broad sides II of the case; and, with the folding on the lines 3^a, 3^c of the margins so that the portions thereof which 65 respectively flank I and II are perpendicular thereto, and also a tucking in of the small triangles at I^a, a case will exist having its narrow sides III each comprising overlapping portions as shown; and these may 70 be secured together to complete the body by gluing, stitching, etc. (not shown). It is desirable to stiffen both extremities of the blank (especially the one which is to form 75 the mentioned flap), for which purpose said 75 extremities are folded over on lines 3^d, 3^e and preferably cemented down. That end portion of the blank where this latter folding is done on line 3^d forms said flap, IV, 80 and this is made as wide only as the adjoining side II of the case and further stiffened by cutting on lines 3^f and folding over the outlying portions on lines 3^a and cementing them down. Generally the blank will be 85 formed of some pliable sheet material, as 85 silk fabric, leather, a decorated or other special and attractive form of paper etc.; and one purpose in stiffening the flap IV is to reinforce it and prevent its corners becoming "dogeared" or curled up in handling. I 90 preferably provide, in combination with the case, a strap which encompasses it in a manner to embrace its two ends and which is slidable around the case and has the flap IV 95 connected therewith. This strap 4 is in 95 Figs. 1 and 2 a flat band (as a ribbon) having a decorative knot 4^a tied therein, the band being passed through a hole 5 in the stiffened edge of the flap which may be sufficiently smaller than the band is wide so that 100 constricting of the band thereby is sufficient to afford such a grip of the flap on the band that in the sliding of the latter they move together. The strap is shown in Fig. 1 slid 105 around to a position where it has shifted the flap to open position; in Fig. 2, the strap is slid around to where it has shifted the flap to closed position. In order to facilitate removal of the empty package 2 and replacement of a filled one without interrupting the continuity of the strap, the strap 110 may be elastic, enabling it to be slipped en-

tirely out of its normal position, obstructing the entrance end of the package.

Figs. 7-10: Here the case is formed by two elongated blanks, 6 and 7, one as wide as the package 2 is wide and the other as wide as the package is thick. The ends of each may be folded over and cemented down to stiffen them, as at 6^a, 6^b, 7^a, 7^b. One traverses the other at right angles to form the bottom I of the case. Then their projecting portions are bent up into perpendicular relation to the bottom to form the broad sides II and narrow sides III of the case. Then these portions are stitched together, as at 8, at 15 their meeting edges, leaving a flap IV substantially the same as already described. And to this flap, embracing the case, is secured in any manner as by passing it through a hole 9 in the flap and tying a knot, a strap 20 10. This strap is in this example shown as a cord, which of course may be of any fancy pattern.

The stiffening of the flap in each of the forms is designed not only to prevent "dog-earing" or curling in handling but so as to leave a substantially rectangular panel (3^x in the first form and 6^x in the second) which

extends clear across and at the end of the flap and which will preserve said end extended and hold it in definite shape notwithstanding the pull exerted by the endless strap when the flap is thereby shifted to open or closed position.

Having thus fully described my invention what I claim and desire to secure by Letters Patent is:

A rectangular case adapted to receive a package of cigarettes and formed of flexible material and with a bottom and an open end opposite thereto and two broad and two narrow sides upstanding from said bottom and a flap projecting from one broad side across said open end and overlapping the other broad side and having its extremity for its full width formed as a substantially rectangular relatively stiff panel, in combination with an endless strap embracing the case in a plane to traverse its bottom and said end and said broad sides and shiftable around the case and attached to the panel of said flap.

In testimony whereof I affix my signature.

EDWARD J. READING.
